UNITED STATES PATENT OFFICE.

PAYSON IRWIN, OF NEW YORK, N. Y.

METHOD OF TREATING METALLIC CONTAINERS TO MAKE THEM CAPABLE OF HOLDING HIGH VACUUMS.

Application filed April 24, 1923. Serial No. 634,377.

To all whom it may concern:

Be it known that I, PAYSON IRWIN, a citizen of the United States, residing at New York city, in the county of New York and State of New York, have invented new and useful Improvements in Methods of Treating Metallic Containers to Make Them Capable of Holding High Vacuums, of which the following is a specification:

- 10 This invention relates to a method of treating metals to make them capable when formed into receptacles, of maintaining high vacuum conditions. It has heretofore been impracticable to utilize metallic containers 15 for maintaining such conditions, due to the presence of occluded air which normally exists in the surface pores of all metals and which gradually escapes, impairing the vacuum.
- 20 One of the objects of the invention is to provide means for the removal of this occluded air.

A further object of the invention resides in the contemporaneous removal in vacuums, 25 from a metallic vessel, of said occluded air, and the retention of vacuum conditions within said vessel.

The method is exemplified by its application to the manufacture of containers 30 thermally insulated by vacuum although this is only one of many ways in which the invention can be carried out.

In the drawings:—

Figure 1 is a longitudinal view in section, largely diagrammatic of a vacuum chamber in which a container to be thermally insulated by vacuum is positioned for treatment.

Figure 2 is a sectional view taken along 40 the line 2—2 of Figure 1.

Referring now in detail to the several figures, the numeral 1 represents a casing forming a chamber 2 which is in communication by means of the conduit 3 with a vacuum producing means of any approved type. The casing 1 is provided with a removable end 4, fitting thereagainst in an air-tight manner and removable for the insertion of the object to be treated. The opposite end of the casing 1 is furnished with a diaphragm 5 which is normally maintained flat but which, when released, is capable of bulging inwardly through atmospheric pressure. The diaphragm is held

against the end of the casing 1 in any suitable manner, such as for instance, between the annular flanges 6 and 7 provided respectively at the end of said casing and at the base of a spider 9, the central portion of which is bored for the reception of a stud 10, having its inner end affixed to the diaphragm 5. In the illustration the central portion of said diaphragm is thickened to provide adequate thickness for engagement by said stud. A wing nut 11 screws upon said stud and abuts against the central portion of the spider 9 to hold the diaphragm 5 in a substantially flat condition. Release of the diaphragm is accomplished by unscrewing said wing nut.

The container to be treated consists preferably of a blank of relatively thin metal which is doubled upon itself, as shown at 12, by any suitable means, to form an annular chamber which terminates in an open tubular extension 13 of small dimension and preferably arranged substantially axially of said annular chamber. The removable end 4 of the casing 1 is suitably apertured at 14 for the passage of an electrode 15 formed at its inner end with a mushroom-shaped head 16 adapted to engage with the inner end surface of the container 12 and assist in holding the latter in position. A second electrode 17 extends through an aperture 18 in the side wall of the casing, said electrode being formed with a perforated head 19 adapted to fit around the tubular extension 13 of the container to be treated and to cooperate with the electrode 15 in holding the vacuum container in place. A bar 20 or other appropriate means is provided within the casing 1 to support the tubular extension 13 and to serve as an anvil against which the extension is mashed or compressed to close the passage therethrough when said extension is acted upon by the sealing means which consists of the roller 21 rotatably mounted upon a stem 22, fixed to the diaphragm 5.

When it is desired to treat a metallic container, the end 4 of the casing 1 is removed, together with the electrode 15 and the container to be treated is placed within the casing 1, with its tubular extension 13 extending through the perforation in the head 19 of the electrode 17. The removable head 4 is then secured in place upon the casing, and

the electrode 15 is pushed inwardly until it snugly engages the container, holding the latter against displacement. Air is evacuated from the casing 1 through the conduit 3 and a current is passed through the electrodes 15 and 17 heating the walls of the container, opening the pores thereof and driving out, by expansion, the occluded air entrapped in said pores. It is immaterial to the invention whether the exhaustion of air from the casing 1 and the heating of the container take place simultaneously or in sequence, it being essential only that the proper degree of vacuum exists at the time the container attains the right temperature.

When the desired degree of vacuum has been reached the electric current is discontinued the wing nut 11 is unscrewed from the stud 10 to permit the diaphragm 5 to be bulged inwardly by atmospheric pressure and to carry the roller 21 over the tubular extension 13 to mash the latter between said roller and the bar 20, thus sealing the annular space within the container against the entrance of air. Here again it is immaterial whether the current be turned off before or after the sealing operation. It has been found that metal of which the container is formed and from which the occluded air has been eliminated by my improved method possesses a greater degree of hardness and elasticity than the same metal, not so treated.

My invention therefore includes, not only the method of producing a container thermally insulated by vacuum, but also the method of treating any similar metallic article in order to temper the metal of which such article is formed and to render it capable of maintaining high vacuum conditions, the method contemplating the steps of establishing the vacuum and heating the

metallic container or other similar article in vacuo until the occluded air has been driven out, even though the sealing of the vacuum within said article takes place as a separate or subsequent operation.

Having described my invention what I claim as new and desire to secure by Letters Patent, is:

1. The method of treating a metallic container to make it capable of maintaining high internal vacuum conditions after having been sealed in vacuums, which consists in establishing vacuum conditions within said container, heating the walls of said container, and continuing the maintenance of vacuum conditions during the heating period until the desired degree of vacuum is obtained.

2. The method of treating a metallic container to make it capable of maintaining high internal vacuum conditions after having been sealed in vacuums, which consists in establishing vacuum conditions within said container, heating said container, continuing the maintenance of vacuum conditions during the period of heating until the desired degree of vacuum is obtained, and sealing said container in vacuums.

3. The method of treating a metallic container to make it capable of maintaining high internal vacuum conditions after having been sealed in vacuums, which consists in establishing continuous vacuum in and around said container, and successively heating said container in vacuo to cause the escape of occluded air from the metal walls thereof and sealing said container in vacuums.

In testimony whereof I have hereunto set my hand.

PAYSON IRWIN.
